UNITED STATES PATENT OFFICE.

FRANK CULOTTA, OF MELROSE PARK, ILLINOIS.

ENVELOPE.

Application filed October 20, 1926. Serial No. 142,878.

My invention relates to envelopes of the type used for correspondence, and more particularly to the class of envelopes used by business firms in writing to dealers, customers and prospects, it being my main object to use the envelope as a medium for advertising.

A further object of my invention is to so design the novel envelope that its exterior 10 may impart an effect of privacy, yet once opened the advertising matter would be in evidence.

A still further object of the invention is to so construct the novel envelope that a 15 quick movement to open the same will result in a full display of the advertising matter and ready access to the letter or other enclosure in the envelope.

A final but nevertheless important object 20 of the invention is to design the novel envelope on very simple lines, making it easy to handle and inexpensive to manufacture.

With the above objects in view, and any 25 others that may suggest themselves from the specification and claims to follow, a better understanding of the invention may be gained by reference to the accompanying drawing, in which—

Figure 1 is a perspective view of the novel 30 envelope, as closed and sealed;

Fig. 2 is a perspective view of the same before closing;

Fig. 3 is a plan view of the envelope developed, or in blank;

Fig. 4 is a vertical section of Figure 1;

Fig. 5 is a section on the line 5—5 of

Figure 4;

Fig. 6 is a view similar to Figure 2 of a modification; and

Fig. 7 is a view of the same, similar to Figure 3.

Referring specifically to Figures 1 and 5, the novel envelope is cut from a single sheet and creased on the lines 10 to define, when 45 folded in the directions of the arrows in Figure 2, a frontal section 11, a back section 12, lateral wings 13 and 14, and a top flap 15.

The exterior of the envelope blank is printed on the frontal or back section in the 50 manner of the customary business correspondence envelope, that is, with the card of the sender on the corner of the frontal section or in the center of the back section; and the wings are printed with advertising mat-

ter; folded in upon the frontal section, and 55 sealed in a lap-joint. The interior of the back section 12 is also printed with advertising matter, glued along the portions 12^a and 12^b, folded in upon the already sealed wing assembly, and sealed to the latter opposite the glued sections 12^a and 12^b.

The top flap 15 is gummed on its inner surface, then folded down—in dried state—upon the already assembled wings 13 and 14 and the back section 12, and the combination 65 passed with its end through a perforating machine, the effect thereof being indicated at 16. Or, the perforations may be made when the blank is cut, as indicated in Figure 3.

When the envelope is received from the 70 mill by the sender, it bears no evidence of advertising matter; and when a letter has been written it is inserted into the envelope by opening the top flap 15 and then sealing the latter. When the letter reaches its 75 destination, the recipient tears off the end of the envelope along the line of perforations. This act severs all the plies, affording immediate access to the letter inside and allowing the back section 12 to swing away 80 and fully expose the advertising matter on the inner surface thereof as well as that on the folded wings 13 and 14.

In the form of envelope described above, the end, which is relatively narrow, is for 85 this reason torn off quickly, affording a more ready access to the letter. Where quick access is not essential, I prefer to use the modification of Figures 6 and 7, which opens along the longer side of the envelope, 90 although constructed on the same principle as the envelope first described. While it may take slightly longer to tear the longer strip in the modification, this type of envelope has the advantage of a wider opening for the 95 insertion or removal of the contents. I am therefore illustrating both forms of the envelope, in order to show the adaptability of my invention to either type.

An envelope is thus had which itself bears 100 the advertising matter, without sacrificing useful space. The advertising matter being inside is concealed during transit, and the letter therefore retains its air of privacy. By the combining and joint perforation of 105 the assembled plies, the letter may be neatly opened without the use of shears or other implements, the contents readily reached

and the advertising matter incidentally observed. While the sides of the back section 12 are not sealed to the balance of the envelope, and access is possible to the interior surfaces which bear the advertising matter, in the event that an unauthorized person shows familiarity or curiosity, such access is not open to the letter or other private contents of the envelope, since the ends 10 of the pocket therefor are sealed at the mill by the gluing of the sections 12^a and 12^b as described. Being of one piece the novel envelope requires but little labor to cut and print, is easy to handle and use, requires 15 no securing tabs, fasteners or other devices apt to get caught or loosened during handling or in the mails, and occasions no extra expense or change in methods of conducting correspondence. The envelope 20 therefore constitutes an efficient medium for

advertising matter intended for those receiving private mail.

I claim:—

An envelope having a frontal section, lateral wings formed thereon and folded rearwardly upon the same, a rectangular back section equal in size to and folded from the bottom of the frontal section upon said wings and sealed to the latter at the top and bottom only, and a gummed closing flap extending from the top of the frontal section 25 adapted to fold upon and be sealed to the top of the back section, said flap and assembly receiving a common line of perforations whereby the assembly will be laid open to 30 expose the inner faces of the several parts when the envelope is opened by tearing along the line of said perforations.

In testimony whereof I affix my signature.
FRANK CULOTTA.
